COMBINED CLOTHES RECEPTACLE AND EXTRACTOR FOR LAUNDERING MACHINES

Charles H. Hays, Jr., Northeast, Pa., assignor to Jamestown Metal Equipment Company, Inc., Jamestown, N. Y., a corporation of New York

Original application December 4, 1939, Serial No. 307,397. Divided and this application June 8, 1943, Serial No. 490,059

3 Claims. (Cl. 210—76)

1

This invention relates to an improvement in material containing receptacles of laundering machines and is a division of my Patent No. 2,361,767, granted October 31, 1944.

The invention is particularly directed to, and has for its objects, the provision of a receptacle usable, in desired successive manner, for washing, rinsing, and drying operations. When used in a washing operation, the receptacle is held stationary by reason of being mounted on a suitable support. A number of openings in the base of the receptacle are fluid sealed by the support, and the receptacle is adapted, during this operation, to contain a cleaning liquid, as well as material to be cleaned. Use in a rinsing operation necessitates emptying the receptacle, this being accomplished by raising it from the support, uncovering the openings in the base thereof, and allowing the fluid to flow from the receptacle through the openings. The receptacle, when used in a drying operation, is centrally mounted and provided with means for its rotation at relatively high speed. In this connection, the receptacle must be of such proportions as to be capable, during rotation, of retaining the materials therein and, at the same time, of providing means, in the form of liquid carrying passages, for conveying the liquid extracted from the material out of the receptacle, such liquid carrying passages being in addition to the openings in the base of the receptacle. To eliminate undue vibration from uneven distribution of the material during the drying or extracting operation, the receptacle is weighted at, or adjacent, its base, such weight being below the drive mounting of the receptacle.

Additional objects and advantages of the invention will be more fully understood from a consideration of the following specification, taken in conjunction with the accompanying drawings; and in which

Fig. 1 is a side elevational view of a laundering machine containing a receptacle that embodies one form of the invention, parts being broken away and sectioned to disclose certain of the receptacle details;

Fig. 2 is a plan view of the receptacle shown in Fig. 1; and

Fig. 3 is a vertical sectional view, taken substantially as indicated by the line 3—3 of Fig. 2.

Referring more particularly to the drawings, the reference numeral 10 is employed to generally designate a laundering machine in which one form of the invention is embodied. The machine, for purposes of disclosure of the present

2

invention, includes a casing 11, in the lower portion 12 of which is located a drive mechanism by which the various laundering operations are caused to be performed. The upper portion of the machine is formed by a substantially circular splash ring 13 closed by a bottom member 14. Centrally of the member 14 is a flanged opening 16 of prescribed diameter. An outlet 17, near the rim of the member 14, provides a drainage connection. Projecting upwardly through the opening 16 is a cylindrical sleeve-like member 18. Slightly above the flanged opening 16, the member 18 is fitted with a receptacle support 19. This support may, as shown in the drawings and for convenience of manufacture, take the form of a saucer. On the inner rim 21 of this support may be located a suitable gasket 22. Openings 23 in the base of the support are arranged in a circle of a diameter approximately 10 that of gasket 22, and is greater than that of the flanged opening 16. The frame member 18 projects well up into the circular compartment formed by the splash ring 13 and bottom member 14, and encloses concentric drive members 24 in the form of an agitator drive shaft 24 and a receptacle drive sleeve 26.

Through a structure set forth in the aforementioned patent, the sleeve 26 serves, under certain conditions, as a support for a material receptacle 27. This receptacle includes a base 28, centrally of which is an upwardly extending column 29. In the top of this column is a finished spherical surface 31 that serves as a seat for a correspondingly shaped element located on the upper end 35 of the receptacle drive sleeve 26. The base 28 may, as shown in the drawings, be inclined downwardly toward the column 29, and at a low point 30 a series of openings 32 are provided. The under face of the base is formed with a circular area that is contoured to seat on the gasket 22 carried by the support 19, the openings 32 being through this area and being thus closed at their lower ends by said gasket when the receptacle is positioned on the support.

The base 28 is provided with a uniformly distributed weight 30 located preferably at, or adjacent, its circumferential edge, which serves to provide a stabilizing effect when the receptacle is rapidly rotated and with an unevenly distributed load. The receptacle walls 33 are shown as separately formed from the base 28, being secured thereto by suitable screws 34. To provide a liquid tight joint between the walls and base, said base may be grooved to receive packing 36, substantially as shown. The walls 33 extend up-

wardly and terminate in an inwardly directed flange 37, finished by a smooth, rolled edge or bead 38. Thus, the diameter of the opening into the receptacle is considerably less than the diameter of the walls 33. Uniformly spaced around the walls 33 are flutes 39. Each of these flutes, adjacent the base wall 28, provides a narrow and shallow recess 41. These recesses become wider and deeper as they approach the top of the receptacle and, being cut away at their upper ends near the flange 37, provide a multiplicity of openings 42. The purpose of the flutes 39 is to provide a number of upwardly and outwardly inclined channels for the passage of liquid from the receptacle by centrifugal force during high speed rotation of the receptacle in the material drying operation. There is no tendency for the material being dried to move upwardly of the side walls 33, since they are substantially vertical, as shown, or may even be inclined slightly inwardly, and in addition the in-turned flange 37 provides a surface for holding any of the material in the receptacle should circumstances of operation cause such material to work upwardly of the walls 33.

It is evident from the foregoing that the receptacle may be utilized in a washing operation when seated on the support 19, and will retain the washing liquid and the material to be washed during such operation. Furthermore, the receptacle, being weighted at its base and provided with a drive suspension not only above the base but above the center of mass of the receptacle and any material and liquid contained therein, will have little or no tendency to vibrate during high speed rotation. The flutes in the side walls of the receptacle are so designed and disposed as to provide adequate passage for the rapid removal of liquid from the material within the receptacle during the drying operation.

Although I have shown and described only one form of a receptacle for use in laundering machines, it will be understood that modifications or variations of the structure shown may be made and are contemplated insofar as they are within the spirit and scope of the invention as defined in the annexed claims.

Having thus set forth my invention what I claim as new and for which I desire protection by Letters Patent is:

1. In a laundering machine, a rotatable receptacle comprising a circular base having smooth surfaced side walls extending substantially perpendicular to said base and terminating in an inturned rim, a plurality of outwardly offset flutes formed in said side walls and extending radially outwardly of said receptacle, said flutes extending from said base to adjacent said rim and terminating at their upper ends in apertures which provide for liquid egress from said receptacle at a point below said rim, and a column projecting upwardly from the center of said base, said column being adapted to receive and engage a drive member for said receptacle.
2. In a laundering machine, a rotatable receptacle adapted to contain liquid, said receptacle comprising a circular base having smooth surfaced substantially vertical side walls, an inturned rim forming a continuation of the top of said side walls and defining a restricted opening into said receptacle, and a plurality of flutes formed from said side walls and directed radially outwardly of said receptacle, said flutes extending from adjacent said base to adjacent the upper edge of said walls, said flutes being closed at their lower ends and terminating at their upper ends in side wall liquid discharge apertures, and being of increasing width and depth from said lower ends to said apertures.
3. In a laundering machine, a rotatable receptacle adapted to contain liquid, said receptacle comprising a circular base, smooth surfaced substantially vertical side walls joined to said base, an inturned rim formed integral with the top of said side wall and defining a restricted opening into said receptacle, a plurality of flutes formed from said side wall and directed radially outwardly of said receptacle, said flutes cooperating with said side walls to provide an interior surface in said receptacle consisting of grooves spaced by relatively extending smooth areas, said flutes being closed at their lower ends adjacent said base wall and terminating short of said inturned rim and being of increasing width and depth from their lower to the upper ends, the wall forming the upper end of each flute being cut away from the side wall of said receptacle to provide discharge apertures.

CHARLES H. HAYS, JR.
